UNITED STATES PATENT OFFICE.

LOUIS M. GRAFE, OF ST. LOUIS, MISSOURI.

VENTILATED SEAT PAD.

Application filed February 11, 1924. Serial No. 691,882.

To all whom it may concern:

Be it known that I, LOUIS M. GRAFE, a citizen of the United States, and a resident of the city of St. Louis and State of Missouri, have invented a new and useful Improvement in Ventilated Seat Pads, of which the following is a specification.

My invention relates to ventilated seat pads for automobiles and has for its principal object a ventilated seat pad that will be simple in construction, inexpensive to manufacture and that will be strong and durable and that will be well ventilated. The invention consists principally in securing to seat pads of any suitable construction (preferably some sort of mesh work) tubular members having perforated walls. The invention further consists in the seat pad and in the parts and combinations of parts hereinafter described and claimed.

In the accompanying drawing,

Fig. 1 is a perspective view of a seat pad embodying my invention,

Fig. 2 is a partial sectional view taken through one of the tubular spacing members,

Fig. 3 is a perspective view of a modified form of spacing member,

Fig. 4 is a view similar to Fig. 2, showing said modified form of spacing member, and

Fig. 5 is a side elevation, showing the pad in place on an automobile seat.

The seat pad shown in the accompanying drawing comprises seat and back members 1 hingedly secured together and adapted to rest against an automobile seat 2 and the back 3 thereof. These members are of any suitable construction, preferably meshwork of straw, cane, rattan or the like. Preferably the weave is very loose so as to permit the passage of air through the members of the pad.

Secured to the seat and back members 1 are a number of tubular spacers A, preferably of light metal. As shown in Figs. 1 and 2, each spacer comprises a hollow shell 4 having extended openings 5 through the walls thereof. The base 6 of each shell 4 is provided with an interiorly threaded lug 7. A disk 8 or cap is provided for securing each shell 4 in place. Each disk 8 has a stem 9 that projects through an opening in the mesh work of the seat or back member 1, the end of the stem being threaded into the threaded lug 7 of the shell 4. Thus the

shell 4 and the disk 8 or cap may be drawn tightly against the seat or back member.

In the form shown in Figs. 3 and 4, each spacer A is a hollow shell 20 that has a top cover 21 and a bottom cover 22. Tabs or prongs 23 are struck up from one cover. The tabs 23 of the several shells 20 are extended through holes in the meshwork of the seat and back members 1 and bent over against said members to secure the shells 20 in place. A suitable cover 24 of cloth or the like may be placed over the tabs 23 of each shell to prevent them from injuring the clothes of a person sitting on the seat.

The above described seat pad is adapted for use in covering the seats of automobiles and the backs of said seats. The spacers A space the seat and back members away from the automobile seat and back and permit circulation of air behind both members of the pads. The spacer shells themselves are perforated and air is permitted to circulate therethrough. The caps or tops of the spacer shells conduct heat away from the person sitting on them. The spacer shells are far enough apart from each other that the pads are free to yield and no discomfort is felt by reason of the presence of the spacer shells.

Obviously the form of the shells may be changed and other changes may be made from the construction shown without departing from my invention and I do not wish to be limited to the precise construction shown.

What I claim is:

1. A seat pad comprising a mesh work member and a multiplicity of spacers secured to the meshwork body thereof, whereby said pad is spaced away from the seat on which it is placed.

2. A seat pad comprising a meshwork member and a multiplicity of spacers secured to the body thereof by means passing through said meshwork, whereby said pad is spaced away from the seat on which it is placed, said spacers having perforated walls.

3. A meshwork pad for the seats of automobiles and the like having a multiplicity of metal spacers secured thereto, said spacers having perforated walls and having portions that extend through the meshwork to secure the spacers in position.

4. A seat pad comprising woven seat and back members hingedly secured together and

a plurality of spacers secured to the body portions of said members, whereby said pad is spaced away from the seat on which it is placed.

5. An automobile seat pad comprising a seat member of meshwork, spacers therefor, said spacers comprising hollow metal shells each having a perforated lug in its base and

a cap for securing each spacer in place, each of said caps having a stem that extends 10 through an opening in the seat member and is threaded into the lug of a shell.

Signed at St. Louis, Missouri, this 8th day of February, 1924.

LOUIS M. GRAFE.
